UNITED STATES PATENT OFFICE.

GEORGE H. DUFOUR, OF OAK PARK, ILLINOIS, ASSIGNOR TO MARSHALL FIELD & COMPANY, OF CHICAGO, ILLINOIS, A CORPORATION OF ILLINOIS.

FINGER GUARD FOR PRINTING PRESSES.

1,407,132.

Specification of Letters Patent. Patented Feb. 21, 1922.

Application filed June 24, 1920. Serial No. 391,315.

To all whom it may concern:

Be it known that I, GEORGE H. DUFOUR, a citizen of the United States, residing at Oak Park, in the county of Cook and State 5 of Illinois, have invented certain new and useful Improvements in Finger Guards for Printing Presses, of which the following is a specification.

This invention relates to a guard to be associated with a printing press to bar the introduction of the fingers of the operator into the path of a moving part when the press is in operation.

In my application, Serial No. 391,314, of 15 even date herewith, I have described and broadly claimed a device for accomplishing this general purpose.

The present invention accomplishes the same result by mechanism so constructed 20 that the guard member, while controlled by a swinging lever which is in turn subject to a releasable detent, slides to and from barrier position, instead of swinging through an arcuate path defined by the radius action 25 of the lever and guard together, and therefore occupies a smaller area in its action and better adapts the device for embodiment with dimensions appropriate to larger types of presses.

30 In the accompanying drawings—

Figure 1 is a front elevation; and Figure 2 a side elevation of portions of a known type of printing press with which the present invention is immediately concerned.

35 1 represents the bed, and 2 the platen which is moved to and from the bed in a press of known construction; the platen being moved by any suitable means, such, for instance, as the drive wheel 3 periodically 40 thrown into driving relation with shaft 4 and its fly wheel 5 through any suitable means, such, for instance, as a releasing handle or lever 6.

In order to prevent the introduction of 45 the fingers of the operator beneath the platen 2, a guard member 7 is mounted to assume barrier position in relation to the space beneath said platen, and this barrier is preferably in the form of an apron of 50 sheet metal or other suitable material pivoted at 8 upon a controlling lever 9, which is in turn pivoted at 9^a upon a fixed support; so that by swinging to bring the pivotal point 8 of the guard member 7 below

its fixed pivot 9^a, said lever will present the 55 guard member in barrier position, and by swinging to bring said pivotal point 8 above the fixed pivot point 9^a, the guard member will be moved to a position remote from the barrier position and afford access to the 60 space beneath the platen 2 for introduction and removal of the printing die. It will be seen that while the lever 9 swings between its two limits of movement, the guard member 7 slides to and from its respective positions. To insure its proper position, it is provided with a guide 7^a over which it slides, and it is held against this guide by means of the spring 10 anchored at 10^a upon the fixed pintle 8, and bearing at 10^b against the 70 guard member in the direction to yieldingly urge the guard member against the guide.

When it is desired to withdraw the guard member from barrier position, as, for instance, when it is necessary to change the die 75 or printing form, lever 9 is swung to the dotted line position of Figure 2 to cause its detent 11 to catch over the resilient arm 12, where the lever will be held with the guard member presented in the position remote 80 from barrier position until work upon the press is to be resumed. To avoid oversight in returning the guard member to barrier position, the arm 12 is carried by or otherwise connected with the lever 6, so that in 85 starting the machine the guard will be automatically released.

While in the specific arrangement shown the lever 9 and the guard 7 will assume barrier position by gravitation whenever released from the detaining arm 12, it is not necessary that they be so arranged; and whether they are or not, it is preferable to employ means such, for instance, as the spring 9^b which constantly urges the lever 9 in the direction to present the guard member in barrier position. This spring may be conveniently arranged upon the fixed pintle 9^a of the lever with one end anchored to said pintle and the other end engaged 100 over a portion of the lever.

The guard member 7 will normally assume a position sufficiently close to the bed 1 to prevent introduction of the fingers beneath it while admitting the card or other 105 material to be printed, and will remain in this position throughout the printing operation. As a further safeguard, however, the

guard member is made to yield outwardly from the printing position so that there will be no obstruction to prompt withdrawal of the fingers in case they should engage 5 with the lower edge of the guard in withdrawing the card. This may be accomplished by the outward swinging of the entire guard member upon its pintle 8 in opposition to its spring 10, but preferably the 10 lower portion of the guard member is made to yield independently of the outwardly swinging movement of the guard member as a whole, and to this end said lower portion is provided with the pivoted gate 13 which will 15 not swing past vertical position inwardly, but is free to swing from vertical position outwardly. This gate will also yield outwardly in case the fingers are in the path of the guard member while sliding toward barrier 20 position.

15 represents a handle through which to manipulate the guard. 16 is a stop mounted on the press in position to receive the pin 17 carried by the lever 9 and arrest the latter when the guard member reaches barrier position. The outer end of the stop 25 may carry an adjustable head 18 for regulating the position at which the lever 9 is arrested; and since the lever and guard 30 member are so connected as to develop a toggle action, it is obvious that the angle of the lever 9 in its arrested position will determine the lower limit of travel of the guard member and consequently the space left beneath 35 the apron 13 for introduction and removal of the card.

I claim:

1. A guard for printing presses comprising a guard member sliding to and from 40 barrier position and a position remote from barrier position, a pivoted lever connected with and imparting movement to said guard member and a pivot support for said lever; said guard member being pivoted to said 45 lever at a point removed from its pivot support; and said lever swinging vertically to bring its connection with the guard member above and below its pivotal point in presenting the guard member in its two positions aforesaid.

2. A guard for printing presses comprising a guard member sliding to and from barrier position and a position remote from barrier position, a pivoted lever connected 55 with and imparting movement to said guard member, and a pivot support for said lever; said guard member being pivoted to said lever at a point removed from its pivot support; and said lever swinging vertically to bring its connection with the guard member above and below its pivotal point in presenting the guard member in its two positions aforesaid, and having a releasable detent for retaining it in its position above 60 its pivot support.

3. A guard for printing presses comprising a guard member sliding to and from barrier position and a position remote from barrier position, a pivoted lever connected with and imparting movement to said guard member, and a pivot support for said lever; said guard member being pivoted to said lever at a point removed from its pivot support; and said lever swinging vertically to bring its connection with the guard member above and below its pivotal point in presenting the guard member in its two positions aforesaid, and having means normally urging its swinging motion in the direction to present the guard in barrier position. 70 75 80

4. A guard for printing presses comprising a guard member sliding to and from barrier position and a position remote from barrier position, and a pivoted lever connected with and imparting movement to said guard member; said guard member carrying a movable gate that resists movement of the operator's hand toward the press and yields to resistance encountered when carried by the guard member toward barrier 90 position. 95

5. A guard for printing presses comprising a guard member sliding to and from barrier position and a position remote from barrier position, and a pivoted lever connected with and imparting movement to said guard member; said guard member having a gate thereon swinging transversely to the direction of its sliding movement. 100

6. A guard for printing presses comprising a guard member sliding to and from barrier position and a position remote from barrier position, and a pivoted lever connected with and imparting movement to said guard member; said guard member being pivoted to said lever; and springs being provided for both said lever and said guard member, which normally tend to swing them in the direction to present the guard member in barrier position. 105 110

7. A guard for printing presses comprising a guard member sliding to barrier position and a position remote from barrier position, a pivoted lever connected with and imparting movement to said guard member, means normally urging the lever in the direction to present the guard member in barrier position, and an arresting stop against which the lever impinges after bringing the guard member within reach of said barrier position. 115 120

8. A finger guard for printing presses comprising a guard member sliding to and from barrier position, a pivoted lever upon which said guard member is pivoted at a point removed from the pivot of the lever and which develops with said guard member a toggle action, and by such toggle action projects the guard member to its barrier position, and a stop which determines 125 130

the angle of throw of the lever and therefore the barrier position of the guard member.

9. A guard for printing presses comprising a guard member sliding to barrier position and a position remote from barrier position, a pivoted lever connected with and imparting movement to said guard member, means normally urging the lever in the direction to present the guard member in barrier position, and an arresting stop against which the lever impinges after bringing the guard member within reach of said barrier position; the guard member having a movement upon said lever; and said movement being free from the control of said stop.

10. A guard for printing presses comprising a guard member sliding to and from barrier position and a position remote from barrier position, and a pivoted lever connected with and imparting movement to said guard member, having a releasable detent for retaining it with the guard member in said remote position; said guard member having means urging a swinging movement thereof upon the lever toward guard position, and having a guide upon which it

slides and against which it is held by said last-named means.

11. In a hand fed printing press, a guard sliding transversely to the line of feed to and from guarding position, a guide upon which said guard slides, and means acting against the guard to press it against the guide.

12. In a hand fed printing press, a guard sliding transversely to the line of feed to and from guarding position and also having a swinging movement away from guarding position in the direction of withdrawal of the feeding hand, and a guide defining the sliding path of the guard.

13. In a hand fed printing press, a guard sliding transversely to the line of feed to and from guarding position and also having a swinging movement away from guarding position in the direction of withdrawal of the feeding hand, a guide defining the sliding path of the guard, and means yieldingly holding the guard against said guide.

Signed at Oak Park, Illinois, this 21st day of June, 1920.

GEORGE H. DUFOUR
